FOLDING HANDLE FOR CONTAINERS

Styles T. Howard, Jeffersonville, Ind.

Application October 3, 1941, Serial No. 413,454

2 Claims. (Cl. 220—94)

(Granted under the act of March 3, 1883, as
amended April 30, 1928; 370 O. G. 757)

The invention described herein, if patented, may be manufactured and used by or for the Government for governmental purposes without the payment of any royalty thereon.

This invention relates to and has for a purpose the provision of a folding handle, particularly adapted for use on nesting containers and the like.

The important object of this invention, therefore, is to provide a handle that will facilitate carrying the containers from place to place and also facilitate the placing of the container within and removing it from another container or the like.

With the above, and other objects and advantages in view, the invention consists of features of construction, arrangement and operation of parts which will appear in the specification and be finally pointed out in the claims.

While the preferred embodiment of the invention is shown, it will be understood that slight changes in form and minor details of construction may be resorted to without departing from the spirit of the invention and fall beyond the scope of the claims.

Referring now to the drawing in which similar characters and references in the several figures indicate identical parts:

Fig. 1 is a sectional view of the nested containers showing the handle in upright position.

Fig. 2 is a top plan view of a container showing the handle in carrying position.

Fig. 3 is a side elevation of the handle in carrying position, showing the manner in which one container can be supported on the edge of another.

Fig. 4 is a front elevation of the handle in lowered position.

Reference now being had to the drawing by numerals, 10 designates the main receptacle or container, which may be cylindrical or of any desired shape and equipped with the usual handles 11 on the exterior thereof. The container 10 is adapted to have nested therein another container 12. The container 12 is provided with collapsible or folding handles 13 which are adapted to lie against the container 12 when they are in lowered position. The handles 13 are pivotally supported by retaining members or plates 14 which are secured to the container 12 by any well-known means, such as rivets 15 or the like.

The handles 13 are provided with openings 16 which are adapted to receive bails or links 17. The bails 17 are provided with angularly disposed

intermediate portions which are adapted to be received in eyes defined by raised portions 18 of stop members or plates 19 which are secured to the container by any well-known means such as rivets 15. The eyes or raised portions 18 of the plates 19 form stops that limit the upward movement of the handles 13.

For purposes of illustration only, there is shown resting on the bottom of the container 12 a rectangular supporting member 20 which is adapted to receive and support containers 21 which are provided with the usual lids 22. The containers 21 are also provided with folding handles 13, plates 14 and bails 17. Stop members 15 or plates 23 are secured to the containers 21, but the plates 23 differ from the plates 19, in that the eye-forming raised portions 24 thereof are open at the bottom to permit the links 17 to be moved from engagement with the stop members 23, so that the handle 13 can be raised and assume the positions shown in Fig. 1. The handles 13 in this position facilitate the removal of the containers 21 from the container 12. The plates 23 are preferably secured to the containers 21 by rivets 15.

It is obvious that when the receptacles or containers are nested as shown in Fig. 1 that it would be difficult procedure to nest the containers or remove the containers from the nested positions unless folding handles, such as the invention contemplates, are used. Containers 21 can also be placed in the position as shown in Fig. 3, and while in this position they will facilitate the removal of the contents of the container.

While there have been shown and described certain embodiments of the invention, it is to be understood that it is capable of many modifications. Changes, therefore, in the construction and arrangement may be made without departing from the spirit and scope of the invention, as disclosed in the appended claims.

Having thus described the invention, what is claimed as new and desired to secure by Letters Patent is:

1. In combination, a container, a handle pivotally secured to the container, a member secured to the container in spaced relation to the handle and having an elongated eye which is disposed lengthwise in directions toward and away from the handle, a link pivotally secured to the handle and having an angularly-disposed portion extending transversely through the eye and bodily slidably lengthwise of the eye towards and away from the handle and adapted to en-

gage the inner terminal of the eye to limit the pivotal movement of the handle to a position in which it extends laterally from the container.

2. In combination, a container, a handle pivotally secured to the container, a member secured to the container in spaced relation to the handle and having an elongated open eye which is disposed lengthwise in directions toward and away from the handle, a link pivotally secured to the handle and having an angularly-disposed

portion extending transversely through the eye and bodily slidably lengthwise of the eye towards and away from the handle and adapted to engage the inner terminal of the eye to limit the pivotal movement of the handle to a position in which it extends laterally from the container, the link being movable from engagement with the eye to permit the handle to move upwardly about its pivot to substantially vertical position.
